CLAIM

The ornamental design for a pipette device, as shown and described.

DESCRIPTION

FIG. 1 is a front right top perspective view of a pipette device showing our new design;

FIG. 2 is a front view of the pipette device shown in FIG. 1; FIG. 3 is a rear view of the pipette device shown in FIG. 1; FIG. 4 is a top view of the pipette device shown in FIG. 1; FIG. 5 is a bottom view of the pipette device shown in FIG. 1;

FIG. 6 is a right side view of the pipette device shown in FIG. 1; and,

FIG. 7 is a left side view of the pipette device shown in FIG. 1.

The broken lines in all figures and the dash-dot-dash line in FIG. 5 depicts the boundary of the claim and forms no part thereof.

1 Claim, 5 Drawing Sheets
